United States Patent Office.

BENJAMIN CHARLES POLE, OF RICHMOND, VIRGINIA.

Letters Patent No. 83,659, dated November 3, 1868.

IMPROVEMENT IN BUTT-HINGES.

The Schedule referred to in these Letters Patent and making part of the same.

To all whom it may concern:

Be it known that I, BENJAMIN CHARLES POLE, of Richmond, county of Henrico, State of Virginia, have invented a new and useful Improvement in Hinges; and I do hereby declare that the following is a full and exact description thereof, reference being had to the accompanying drawings, and to the letters of reference marked thereon, in which—

Figure 1 represents sectional view of hinge closed.

Figure 2 represents sectional view of hinge opened.

Figure 3 represents perspective view of hinge opened.

Figure 4 represents front view of plate C of hinge.

Figure 5 represents hinged lever E and rod I detached.

Figure 6 represents top view of bed-plate A.

In all, the same letters refer to the same parts.

A is the bed-plate.

B, spring.

b, point at which B is attached to A.

C is the movable plate of hinge.

c c c, eyes in end of plate C, through which the connecting-rod H passes.

D, slot in plate C, in which plays E, the hinged lever.

F is the upper plate of hinge attached to door or lid.

G, pivot connecting E and I, and on which E may work.

H H, are connecting-rods, connecting plate C with F, and spring B with plate C, respectively.

I, rod connected with E by G.

K, top plate, corresponding to bed-plate A.

L is the side of case to which door or lid is hinged.

M is the door or lid.

N, mortise in L.

O, channel for lever E and rod I.

P, channel in bed-plate A to receive plate C when closed.

The nature of my invention is a hinge in which the position of the line of revolution is changed, so that when the door or lid is closed, the hinge will be concealed from view, leaving a smooth, unbroken surface.

To enable others skilled in the art to make and use my invention, I will proceed to describe its construction and operation.

In the fixed side L of case to which the door or lid is to be hinged, I make a mortise, N, of suitable size and shape, in which I insert and securely fasten the bed-plate A, cast of metal, the shape of which is shown in fig. 6. On the upper side of the mortise, I place the plate K, which should be made of steel, and is also fastened by screws to the bed-plate A. To the underside of the bed-plate, in any convenient manner, is attached one end of the spring B, constructed of any convenient shape or kind, the other end of which has an eye in it, through which passes the rod H, which connects it with hinge-plate C. The hinge-plate C, the shape of which is shown in fig. 4, connected at lower end, as above stated, is similarly connected by rod H with

the upper hinge-plate F, which is fastened, in any usual manner, to door or lid M, at a suitable distance from its outer surface. In the slot D of hinge C, plays the hinged lever E, which is hinged to the plates C and F, by rod H, which passes through eye e, (figs. 4 and 5.) Through e of E, fig. 5, is a point which connects E with rod I, so that it may turn upon it. Rod I has a bend or head at the free end, so as to prevent it from escaping from a passage made for it between the bed-plate A and top plate K, and thereby preventing the hinged lever E from being pulled from its proper position, to act upon steel plate K upon opening or closing.

To show the manner in which the hinge operates, having been thus constructed, I suppose the case to which it is applied open, as in figs. 2 and 3, the several parts of the hinge being of such relative size that it will present the appearance therein exhibited. The lid or door is raised or opened in the usual manner, revolving on the rod H, which passes through e, until the upper plate of hinge F comes in contact with hinged lever E, the lid or door then being at right angles with side L of case. Still pressing down, as usual in closing a lid, the plate C descends, as indicated by red dotted line in fig. 2, and the hinge-lever E enters the opening between the bed-plate A and upper plate K, sliding on the upper plate K, and pressing back rod I until the line of revolution c comes into position, as indicated in fig. 1, and the lid or door is shut, the hinge-plate C being in the channel P, cut to receive it in bed-plate A, and the lower part of side L. The joint at c, on which the upper hinge-plate F revolves, is thus below the surface of the side of cover L and lid or door M, which come into close contact, and form an even surface, entirely concealing the hinge from view.

To open the lid or door, proceed as usual, reversing the above operation.

The rod I, by being forced against the side of the bed-plate A and top plate K, prevents the hinged lever from escaping, and the lid or door M from sliding or being pulled from its proper position.

I do not claim any particular shape of the parts herein described, nor the use of any particular kind of spring.

Having described the construction and operation of my improvement, I will now state that

What I claim as my invention, and desire to secure by Letters Patent, is as follows:

The bed-plate A, the spring B, the hinge-plate C with slot D, the hinged lever E, rod I, plate K, hinge-plate F, all constructed, combined, and operating substantially in the manner and for the purpose herein set forth.

BENJAMIN C. POLE.
